UNITED STATES PATENT OFFICE.

ALBERT E. MULLEN, OF NEW YORK, N. Y.

DESIGN FOR A TOILET-ACCESSORY CONTAINER.

Application filed May 1, 1928. Serial No. 26,521. Term of patent 7 years.

To all whom it may concern:

Be it known that I, ALBERT E. MULLEN, a citizen of the United States, residing at New York city, county of New York, borough of Manhattan, and State of New York, have invented a new, original, and ornamental Design for Toilet-Accessory Containers, of which the following is a specification, reference being had to the accompanying drawing, forming part thereof.

The figure is a perspective view of the device of my invention.

I claim:

The ornamental design for a toilet accessory container, as shown.

ALBERT E. MULLEN.
